CONTROL SYSTEMS FOR PARTITIONS
OR THE LIKE

Jean Mercier, New York, N. Y.

Application December 11, 1952, Serial No. 325,494

Claims priority, application France December 20, 1951

22 Claims. (Cl. 268—50)

This invention relates to control systems for partitions and more particularly for bulkhead doors of a ship.

It is among the objects of the invention to provide a relatively simple and dependable control system which provides ready operation from both a remote station and from a local station adjacent the partition to move the latter from one position to another or security position, and also provides for movement of such partition from the local station without possibility of the operator at the remote station interfering with such movement.

Another object is to provide a system of the above type which provides for closing of the partition from the remote station by a manual pumping operation or a simple switching operation.

According to the invention, the control system includes a central or remote control station and a local station, each having means to deliver fluid under pressure to a hydraulic cylinder for operating the partition. A selector valve is provided in the circuit having at least a partition opening position and a partition closing position and is designed when in partition opening position to by-pass the fluid from the remote station back to the reservoir so that the actuation of the fluid delivery means at the remote station will not interfere with the opening of the partition at the local station.

This application is a continuation-in-part of copending application Serial No. 245,367, filed September 6, 1951.

In the accompanying drawings in which are shown one or more of various possible embodiments of the several features of the invention,

Fig. 1 is a circuit diagram of one embodiment of the system,

Fig. 2 is a transverse sectional view of the distributor valve in partition opening position,

Fig. 3 is a view similar to Fig. 1 of another embodiment of the system,

Figs. 4 and 5 are transverse sectional views of the distributor valve of Fig. 3 in partition closing and opening position respectively,

Fig. 6 is a circuit diagram of a modification of the system shown in Fig. 3, and

Figs. 7 and 8 are block diagrams illustrating the circuits shown in Figs. 1 and 3 respectively.

Referring now to Figs. 1 and 2 of the drawings in which is illustratively shown an embodiment of the invention for control of a slidable partition, illustratively the bulkhead door on a ship, the system desirably comprises a central or remote control station 11, preferably located above the water line, for example, on the bridge of the ship, and a plurality of local control stations 12 (one of which is shown) desirably located adjacent the various bulkhead doors to be actuated.

The central control station 11 has a pump 13 and each of the local control stations 12 has a pump 14 controlled respectively by handles 15 and 16. The input of the pump 13 at the central control station is desirably connected by line 17 to a fluid reservoir 18 which pref-

2

erably is located above the level of the pumps 13 and 14 so that fluid may readily be sucked into said pumps upon actuation thereof and the input of each of the pumps 14 at the local control stations is connected to reservoir 18 through branch lines 19. The reservoir has a main return line 21 to which the outputs of the local stations 12 are connected by branch return lines 22.

The output of pump 13 is connected to main feed line 25 and a plurality of branch lines 26 leading to the local stations 12 for actuating the associated bulkhead door 27 are connected to said main feed line 25 through valves 28.

As shown in Fig. 1, each of the branch lines 26 is connected through one-way check valve 29 to junction 31, which in turn is connected by line 32 to port 33 of distributor valve 34 and by line 35 to port 36 of hydraulic cylinder 37 which controls the movement of bulkhead door 27.

The distributor valve 34 desirably comprises a substantially cylindrical hollow body or sleeve 38 having a substantially cylindrical valve member 39 slidably mounted therein. One end of the valve member 39 has a protruding portion 41 to which is affixed one end of a rod 42, the latter extending through end wall 43 of the body 38 and being affixed at its outer end as at 44 to a control lever 45. The lever desirably is positioned adjacent the bulkhead door 27 and is pivoted as at 46 to the bulkhead of the ship adjacent such door. A spring 47 affixed at one end as at 48 to the bulkhead and at its other end as at 49 to the lever adjacent its handle end 51, normally retains the valve member 39 in closed position with its protruding portion 41 against end wall 43. Desirably the lever 45 is designed so that it may be manually pivoted from both sides of the bulkhead door.

The valve member 39 desirably has an axial passageway 53 which extends from one end 54 of the valve member into the protruding portion 41 and a transverse passageway 55 in said protruding portion provides communication between axial passageway 53 and the bore 56 of the hollow body 38.

As shown in Fig. 1, the valve member desirably has an annular groove 57 in its periphery which, when the valve member is in door closing position shown in Fig. 1, provides communication between ports 58 and 59 in the distributor body 38. In addition to such two ports 58 and 59, the distributor body has ports 61 and 62 near the end walls 43 and 63 thereof respectively, which ports are in communication through passageways 53 and 55 when the valve member is in door closing position. The port 33 of the distributor valve is normally sealed by the end 54 of the valve member 39 when the latter is in closed position.

Inlet port 58 is connected by line 65 to the outlet of pump 14 and port 62 is connected by branch line 22 to return line 21 connected to reservoir 18. The port 61 is connected by line 67 to port 68 in hydraulic cylinder 37, said port being positioned on one side of the piston 69 slidably mounted in said hydraulic cylinder 37. The piston 69 desirably has a piston rod 71 connected thereto and extending through end wall 72 of said hydraulic cylinder and is connected to the bulkhead door 27 to actuate the latter. The hydraulic cylinder 37 near the end 73 thereof desirably has a partition 74 which defines a chamber 75 with respect to end wall 73. Chamber 75 in addition to port 36 has a second port 76 connected by line 77 to port 59 of the distributor body. Desirably a ball valve 78 is positioned in chamber 75 and normally retained against port 76 by a coil spring 79. The partition 74 has an opening 81 therein to permit flow of fluid from the chamber 75 into the main cylinder chamber 82 in which the piston 69 is slidably mounted.

Desirably the bulkhead door 27 has a finger 83 which coacts with a switch 84 to actuate the latter when the door is in closed position, the switch controlling an indicating device such as a lamp 85 at the central station 11 to indicate when the door is closed.

In the operation of the system shown in Fig. 1, with the distributor valve 34 in its normal door closing position in which it is retained by spring 47, reacting against lever 45, the bulkhead door may be opened only from the local station 12.

To open the bulkhead door 27 from the local station 12, it is merely necessary to pivot lever 45 in a counter-clockwise direction to move valve member 39 to the position shown in Fig. 2, and to operate the handle 16 of pump 14 to actuate the latter.

When the valve member 39 has been moved to the position shown in Fig. 2, ports 58 and 61 will be in communication through the bore 56 of the distributor valve. In addition, port 62 will be in communication with ports 33 and 59 through annular groove 57.

The fluid forced by pump 14 from reservoir 18 will flow through line 65, ports 58 and 61, line 67 into port 68 of hydraulic cylinder 37 to move the piston 69 therein to the right. As a result, the bulkhead door 27 will be moved to open position through the transmission (not shown) operated by piston rod 71. When piston 69 moves to the right, the fluid in chamber 82 will be forced through opening 81 in partition 74 into chamber 75. By reason of the ball valve 78, port 76 will remain closed and the fluid will flow through port 36, lines 35 and 32 into port 33 of distributor valve 34 and thence through annular groove 57 and port 62, through line 22 to return line 21 back to reservoir 14.

After the door is opened, pump control handle 16 is released to stop the pump and lever 45 is released so that spring 47 will move valve member 39 back to its normal door closing position shown in Fig. 1.

The bulkhead door may be closed from either the central control station 11 or the local control station 12.

To close the door from the local station 12, the control handle 16 is actuated so that fluid will flow from reservoir 18 through pump 14, line 65, port 58 of distributor valve 34, annular groove 57, port 59, line 77 into port 76 of hydraulic cylinder 37, thereby moving ball valve 78 away from such port. The fluid will then flow from chamber 75 through opening 81 in partition 74 into chamber 82 of the hydraulic cylinder. As a result, the piston 69 will be moved to the left to close the door through the transmission actuated by piston rod 71 and the fluid in chamber 82 will be forced out of port 68 through line 67, port 61 of distributor valve 34, passageways 55 and 53, port 62, line 22, return line 21 back to reservoir 18.

Although port 36, which is connected by line 35 to junction 31 and thence to lines 26 and 32, is open when fluid is forced into chamber 75, line 26 will be blocked by one-way check valve 29 and line 32 will be blocked by end 54 of valve member 39 which seals port 33. Hence no fluid will flow through port 36 to interfere with the movement of piston 69.

Any one or more of the bulkhead doors at the local stations may be closed from the central station 11, depending upon the number of valves 28 that are opened. Thus, with the distributor valve 34 in closed position, shown in Fig. 1, it is merely necessary to open the selected control valve 28 depending upon the bulkhead door it is desired to close and to actuate control handle 15 of pump 13. As a result, fluid will flow from reservoir 18, through line 17, pump 13, line 25, open valve 28, line 26, through one-way check valve 29 to junction 31. Although junction 31 is connected by line 32 to port 33 of the distributor valve, as port 33 is closed by end 54 of valve member 39, no fluid will flow through line 32. Fluid will flow from junction 31 through line 35 and port 36 of hydraulic cylinder 37 into chamber 75. By

reason of the spring 79 against ball valve 78, and the pressure of the fluid forced in chamber 75, port 76 will remain closed and the fluid will flow from chamber 75 through opening 81 into cylinder chamber 82 to move the piston 69 therein to the left thereby closing the bulkhead door through the transmission actuated by piston rod 71.

By reason of the switch 84 which is actuated by finger 83 on the bulkhead door 27, an indication will be provided by lamp 85 on the bridge of the ship when the bulkhead door has been closed and at such time control handle 15 of pump 13 may be released and valve 28 closed.

The fluid forced out of the chamber 82 of hydraulic cylinder 37 will pass through port 68 and line 67 into port 61 of the distributor valve, and thence through passageways 55 and 53 through port 62, line 22 and return line 21 back to reservoir 18.

With the system above described, the bulkhead doors may be closed from the central station 11 only when there is no operation at the local station to open the bulkhead doors, i. e., the distributor valve 34 is not in the open position shown in Fig. 2 and the pump 14 is not actuated.

If valve 34 is in door opening position and pump 14 is actuated, fluid will flow through line 65, port 58, bore 56, port 61 into port 68 of the hydraulic cylinder 37 to move the piston therein to door opening position. If the pump 13 is actuated simultaneously, fluid will flow through line 25, valve 28, line 26, check valve 29 to junction 31 and thence through line 32 and 35 to port 33 of distributor valve 34 and to port 36 of hydraulic cylinder 37.

As port 33 will be in communication with port 62 when the distributor valve 34 is in door opening position, shown in Fig. 2, the fluid from pump 13 into port 33 will encounter less resistance to its flow than it encounters when it attempts to flow into port 36, by reason of the fluid under pressure forced into chamber 75 by the movement of piston 69. As a result, the fluid from pump 13 will flow through port 33 to reservoir 18 and hence will not prevent opening of the bulkhead door.

If the pump 13 at the central station and the pump 14 at the local station are operated simultaneously with the distributor valve in closed position, shown in Fig. 1, as fluid will be forced into ports 76 and 36 of the hydraulic cylinder from both pumps, the effect will be additive to move the door to closed position.

The embodiment of the system shown in Figs. 3 to 5 desirably comprises a reservoir 89 desirably at a central control station 95 which preferably is located on the bridge of a ship and which has a pump 93, actuated by control handle 94, with its inlet connected to reservoir 89. By means of a main line 72 which desirably leads into the top of reservoir 89, such reservoir is connected through one-way check valve 90 to reservoir 91 which may be located in the hold of the ship. The check valve 90 is so positioned in line 92 as to prevent flow therethrough from reservoir 91 to reservoir 89. The reservoir 91 is also desirably connected by line 96 to the inlet of a pump 97 also preferably located in the hold of the ship. The pump 97 desirably has a conventional self-contained pressure switch (not shown) which cuts off the power to the pump drive motor 88 when the pressure in the pump output rises above a predetermined amount.

The output of pump 93 is connected by feed line 98 through valve 99 and line 101 to the output of pump 97 and a plurality of local control stations 104, one of which is illustratively shown, is connected by branch feed lines 105 to line 101.

The branch line 105 to the local station 104 shown in Fig. 3 is connected through a check valve 87 to a junction 106 which in turn is connected by line 107 to the port 110 of a pressure accumulator 109 of conventional type such as that shown in Reissue Patent No.

23,343, dated February 20, 1951, a pressure gauge 111 being suitably connected to line 107 to indicate the pressure therein. Junction 106 is connected by line 112 to the inlet port 113 of a distributor valve 114 which desirably has three positions; an intermediate position shown in Fig. 3, a closed position shown in Fig. 4 and an open position shown in Fig. 5.

The distributor valve 114 desirably comprises a substantially cylindrical hollow body or sleeve 115 having a substantially cylindrical valve member 116 slidably mounted therein. The valve member 116 desirably has two arcuate grooves 117, 118 therein, defining end portions 119, 121 and a central portion 122. In addition to inlet port 113, the distributor valve has six ports 123, 124, 125, 126, 127 and 128. In the intermediate position of the valve member 116, shown in Fig. 3, the central portion 122 thereof closes port 113 and communication is provided through arcuate groove 117 between ports 123 and 126, and through arcuate groove 118 between ports 124 and 127. In such intermediate position of the valve member, the port 128 is closed by end portion 121 of the valve member.

The ports 123, 124 and 125 are connected through common line 131 to the return line 132 which is connected to main line 92. The return lines 132 of the distributor valves (not shown) of the other local stations are also connected to line 92. The port 127 is connected by line 134 to port 135 in hydraulic cylinder 136, said port 135 being positioned on one side of the piston 137 slidably mounted in the hydraulic cylinder 136. Piston 137 has a piston rod 138 connected thereto and extending through end wall 139 of the hydraulic cylinder, said piston rod being connected to a bulkhead door 141 through a conventional transmission (not shown) to actuate the latter.

The hydraulic cylinder 136 near the end wall 142 thereof desirably has a partition 143 which defines a chamber 144 with respect to end wall 142. Chamber 144 has a port 145 connected by line 146 to port 126 of the distributor valve 114, and a second port 147 connected by line 148 to junction 149. This junction is connected by line 151 to port 128 of distributor valve 114 and by line 152 to the outlet of one-way check valve 153, the inlet end of which is connected by branch line 154 through manually operated valve 155 to line 98. As shown in Fig. 3, a plurality of branch lines 154 are connected through associated valves 155 to the other local stations 104.

Desirably, a ball valve 161 is positioned in chamber 144 of hydraulic cylinder 136 and normally retained against port 147 by a coil spring 162. The partition 143 desirably has an opening 163 therein to permit flow of fluid from the chamber 144 into the main cylinder chamber 164 in which the piston 137 is slidably mounted.

Desirably the bulkhead door 141 has a finger 166 which coacts with a switch 167 to actuate the latter when the door 141 is in closed position, the switch controlling an indicating device 168 preferably located on the bridge of the ship to indicate when the door is closed.

Although the distributor valve 114 may be actuated in any suitable manner, in the embodiment herein shown, an actuating rod 171 is affixed at one end to valve member 116 and pivotally connected at its other end as at 172 to a control lever 173 pivotally mounted at one end as at 174 and having a handle 175 at its other end, the lever being normally urged downwardly by a coil spring 170 affixed at one end thereto.

The lever 173 between the handle thereof and the pivoted end 172 of rod 171 has affixed thereto one end of a connector member 176, the other end of said connector member extending through the end wall 177 of a cylindrical casing 178 and having a piston 179 affixed thereto. Although a flexible cable could be used for the connector member, in the illustrative embodiment herein shown, a rigid rod is used. A fully extended spring 181 positioned

in said casing 178 encompasses said rod and retains the piston 179 spaced from end wall 177. A rod 182 affixed at one end to the end wall 183 of the casing 178 is pivotally connected at its other end to the mid portion of lever 184 pivoted at one end as at 185. The lever 184 is urged by a spring 180 against a stop 186 and retained thereagainst by means of a latch arm 187 pivotally mounted as at 188 to the bulkhead of the ship and having a finger 189 at one end adapted to extend beneath the free end 191 of lever 184. The other end of the latch arm is positioned adjacent an electro-magnet 193 which is normally energized to retain the finger 189 of the latch arm beneath the lever 184. The coil of the electromagnet is connected through a switch 194, desirably located near the bulkhead door, to one side of a source of potential and through a lead 195 and normally closed switch 196 on the bridge of the ship to the other side of the source of potential.

The coil spring 181 is desirably stronger than coil spring 170 so that when the lever 184 is retained by arm 187 against stop 186, the valve member 116 will be in the intermediate position shown in Fig. 3.

Desirably the lever 173 also controls a switch 197 which is connected from one side of a source of current through an indicating device such as a bell 198 and switch 167 to the other side of the source of current. Thus, upon either up or down movement of lever 173, switch 197 will be closed so that when the switch 167 is closed by the movement of the bulkhead door to closed position, the bell 198 will ring.

The system shown in Figs. 3 to 5 is readied for operation by energizing motor 88 to drive pump 97 and such pump will force fluid from reservoir 91 into accumulator 109 to charge the latter. When the pressure in line 105 reaches a predetermined amount, by means of the conventional pressure switch (not shown), motor 88 will cut off. The system is normally set with latch arm 187 retaining lever 184 in the position shown in Fig. 3 and with the distributor valve 114 in intermediate position. If at this time the bulkhead door should be closed, it may be opened from the local station 104 adjacent such door.

To this end, it is merely necessary to raise handle 175 to pivot lever 173 upwardly, such movement of lever 173 being permitted by reason of the rod 176. As the lever 173 is pivoted upwardly, the valve member 116 will be moved to the position shown in Fig. 5. As a result, fluid will flow from the charged accumulator 109, line 107, junction 106, line 112 to port 113 of the distributor valve 114, the check valve 87 preventing flow through lines 105 and 101.

As port 113 is in communication with port 127 through annular groove 118 in valve member 116, fluid will flow through port 127 and line 134 into port 135 of hydraulic cylinder 136. As a result, the piston 137 will be moved to the right to open the bulkhead door 141 through the transmission from piston rod 138. The fluid in chamber 154 of the hydraulic cylinder will be forced through opening 163 in partition 143 into chamber 144. As port 147 of such chamber is closed by ball valve 161, the fluid will flow through port 145, line 146 to port 126 of distributor valve 114, annular groove 117, port 123, lines 131 and 132 back through valve 90 and line 92 to reservoir 91 and also to reservoir 89.

65 After the bulkhead door is opened the lever 173 may be released and the valve member 116 will be returned to its intermediate position by spring 170.

To close the door from the local station, the lever 173 is pivoted downwardly, moving valve member 116 to the position shown in Fig. 4. Such movement of the lever 173 is permitted by reason of the spring 181 in casing 178 which will be compressed by downward movement of the piston 179 by rod 176. When valve member 116 is in closed position, a circuit will be provided from accumulator 109, through line 107, junction 106, line 112

into port 113 of the distributor valve, through annular groove 117, port 126, line 146 to port 145 of the hydraulic cylinder 136. The fluid under pressure flowing into port 145 will fill chamber 144, being prevented from flowing through port 147 by ball valve 161, and will flow through opening 163 in partition 143 into chamber 164, thereby moving piston 137 to the left to close the bulkhead door through the transmission from piston rod 138. The fluid to the left of piston 137 will be forced from chamber 164 through port 135, line 134 into port 127 of the distributor valve which is in communication with port 124 through annular groove 118 and from port 124 through lines 131 and 132, valve 90 and line 92 to reservoir 91 and also to reservoir 89.

When the door 141 reaches closed position, the finger 166 thereon will close switch 167 so that bell 198 will ring to indicate to the person closing the door that it has reached closed position and he may release the lever 173. As the result of release of such lever, the tensed coil spring 181 will raise the latter and restore the valve member 116 to intermediate position.

In the event the pressure in accumulator 109 should fall below a predetermined amount while the valve 114 is in either the closed or open positions, shown in Figs. 4 and 5 respectively, the pressure switch (not shown) associated with pump 97 will energize the motor 88 which will again rotate pump 97 so that it will deliver fluid into line 112. When the piston 137 has been moved to either extreme open or closed position, the pressure in line 112 will build up. As a result, the accumulator 109 will charge until the pressure in line 105 reaches the cut off pressure of the motor 88 driving pump 97. If the valve is in the intermediate position shown in Fig. 3 and the pressure in accumulator 109 should be below such predetermined amount, the motor 88 will also rotate pump 97 to force fluid into line 112. As port 113 will be sealed by portion 122 of valve member 116, the pressure in line 112 will build up to charge the accumulator 109.

With the system shown in Figs. 3 to 5, the bulkhead door may be opened or closed from the local station, but an operator at the central or remote station on the bridge can only close the bulkhead door.

To close the door from the bridge of the ship with the distributor valve in intermediate position, as shown in Fig. 3, it is merely necessary to open switch 196 on the bridge. As a result, the electro-magnet 193 will be de-energized enabling coil spring 170, through rod 176, casing 178 and rod 182 to pivot lever 184 downwardly against the slight tension of spring 180, such movement of the lever 184 pivoting latch arm 189 in a clockwise direction. Consequently, the valve member 116 will be moved to closed position shown in Fig. 4 and the bulkhead door will be closed in the same manner as previously described when the lever 173 was moved downward manually.

When the bulkhead door is closed, by reason of the actuation of switch 167 by the movement of finger 166 on door 141, a circuit will be completed from such switch to indicating device 168 on the bridge of the ship. When the indicating device 168 is actuated, the operator on the bridge then may close switch 196. As a result, electro-magnet 193 will again be energized to pivot latch arm 187 in a counterclockwise direction. However, as the end 191 of lever 184 has been moved away from arm 189, the lever 184 will remain in its lowermost portion and valve member 116 will remain in closed position and it is not until lever 173 is manually pivoted that spring 180 will raise arm 184 so that end 191 thereof will move by finger 189 to be engaged thereby. It is also to be noted that the bulkhead door can be closed by the opening of switch 194 which also will de-energize electro-magnet 193.

In the event that the motor 88 or pump 97 should break down, and accumulator 109 is discharged, the bulkhead

door may still be closed from the bridge of the ship. For this purpose, it is merely necessary for the valve 155 to be opened and the handle 94 of pump 93 actuated. As a result, fluid will flow from reservoir 89 through pump 93, line 98, valve 155, line 154, check valve 153, line 152, junction 149, line 148 into port 147. The ball valve 161 will be displaced and fluid will flow into chamber 144, through opening 163 in partition 143 into chamber 164 to move the piston 137 to the left to door closing position as previously described.

If with the motor 88 or pump 97 disabled and accumulator 109 discharged, a person adjacent the bulkhead door should desire to close or open the same, he need merely call the bridge and advise them accordingly. The closing of the bulkhead door from the bridge may be accomplished by the opening of valve 155 and actuation of pump handle 94 as previously described. To affect opening of the bulkhead door, the person adjacent the latter need merely raise the lever 173 to move the valve member 116 to the door opening position shown in Fig. 5. The attendant on the bridge of the ship would then open the valve 99 and actuate the pump handle 94. As a result, fluid would flow from reservoir 89 through pump 93, line 98, open valve 99, lines 101, 105 and 112 into port 113 of the distributor valve and through annular groove 118 and port 127 as previously described to move the bulkhead door to open position.

In the event a bulkhead door is closed and a crew member desires to pass therethrough, he need merely raise lever 173 as previously described, to open the door. When lever 173 is released, the valve member 116 will return to intermediate position and the door will remain open. To insure that the door will automatically close, it is merely necessary to open switch 194 so that the valve member will move to closed position. In such event if a crew member should open the door to pass therethrough, after he released lever 173, the valve member 116 would return to closed position as the de-energized electromagnet 193 would not hold lever 184 that otherwise will retain the valve member 116 in intermediate position.

The embodiment of the device shown in Fig. 6 is substantially identical to that shown in Fig. 3 except that a pump 201 is provided at each of the local stations to operate the bulkhead door. In the circuit shown in Fig. 6, in which parts corresponding to those in Fig. 3 have the same reference numerals primed, a one-way check valve 202 is positioned in line 105', such valve permitting flow only from the pump 97' to the line 105'. In addition, a one-way check valve 203 is positioned in line 112' between port 113' and junction 106 to permit flow of fluid from such junction into port 113'. A line 204 is connected at one end to line 112' between port 113' and check valve 203 and at its other end to the outlet of a one-way check valve 205, the inlet end of which is connected to the outlet of pump 201 supplied with fluid by line 207 connected to line 92' from the reservoir 91'.

The operation of the system shown in Fig. 6 is substantially identical to that of the system shown in Fig. 3. However, in the event the main pump 97' should fail, the bulkhead door may still be actuated by the manual operation of the pump 201. Thus, fluid will flow from reservoir 91' through pump 201, check valve 205 to port 113' of the distributor valve to move the bulkhead door in direction depending on the setting of the distributor valve 114'. The check valve 205 prevents fluid from flowing into pump 201 through line 204 during normal operation of the system. The check valve 203 prevents fluid from flowing into the accumulator when pump 201 is operated and the check valve 202 prevents leakage of fluid from the accumulator in the event line 103' is broken.

As many changes could be made in the above construction, and many apparently widely different embodiments of this invention could be made without departing

from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A control system comprising a local control station, a remote control station, a pair of pumps each having an outlet, a source of fluid for said pumps, one of said pumps being at the remote station, a hydraulic cylinder having a piston slideable therein, said cylinder having a port on one side of said piston and a pair of ports on the other side of said piston, means connecting the outlet of said remote station pump to one of the pair of ports of said cylinder, a distributor member having a pair of ports connected respectively to the other ports of said cylinder, said distributor member also having an inlet port connected to the outlet of the other pump and a return port connected to the cylinder port to which the remote pump is connected, means in said distributor member movable from one operating position to another to connect said inlet port to one or the other of the pair of ports in said distributor member respectively, said distributor member having an additional port connected to said fluid source, said means in said distributor member when in one of said operating positions closing said return port and when in the other of said operating positions connecting said return port and said additional port.

2. The combination set forth in claim 1 in which valve means are provided to permit flow of fluid from the outlet of the remote station pump into the port of said cylinder to which the outlet of the remote station pump is connected but to restrain flow of fluid out of said port to said outlet.

3. The combination set forth in claim 1 in which said hydraulic cylinder has a partition near one end thereof defining two chambers, said piston being slideable in one of said chambers, said partition having an opening providing communication between said chambers, and said pair of ports lead into the other chamber.

4. The combination set forth in claim 3 in which valve means are provided in said other chamber to permit flow of fluid into the other port of the pair of ports in said cylinder and to restrain flow of fluid out of said other port.

5. The combination set forth in claim 3 in which valve means are provided in said other chamber to permit flow of fluid into the other port of the pair of ports in said cylinder and to restrain flow of fluid out of said port, said valve means comprising a ball in said other chamber and resilient means normally retaining said ball seated over said other port.

6. The combination set forth in claim 1 in which means are provided normally to urge the means in said distributor member to one of said operating positions and manually operated means are provided to move the means in said distributor member to the other operating position.

7. The combination set forth in claim 1 in which said distributor member is positioned at the local station and in which means are provided normally to urge the means in said distributor member to one of said operating positions and manually operated means are provided to move the means in said distributor member to the other operating position.

8. A control system comprising a local control station, a remote control station, a pump at each of said stations, each of said pumps having an outlet, a fluid reservoir for said pumps, a hydraulic cylinder having a piston slideable therein, said cylinder having a port on one side of said piston and a pair of ports on the other side of said piston, means connecting the outlet of said remote station pump to one of the pair of ports of said cylinder, a distributor member having a pair of ports connected respectively when in said operating positions, said distributor member having an additional port connected to said fluid source, said means in said distributor member closing said return port when in intermediate and one of said operating positions and connecting said return port and said additional port when in the other of said operating positions and a pressure accumulator connected to the inlet port of said distributor member.

respectively to the other ports of said cylinder, said distributor member also having an inlet port connected to the outlet of the local station pump, and a return port connected to the cylinder port to which the remote station pump is connected, means in said distributor member movable from one operating position to another to connect said inlet port to one or the other of the pair of ports in said distributor member, said distributor member having an additional port connected to said reservoir, said means in said distributor member when in one of said operating positions closing said return port and when in the other operating position connecting said return port to said additional port.

9. The combination set forth in claim 8 in which said piston controls a piston rod, a slidably mounted door is provided operatively connected to said piston rod and movable thereby from open to closed position, an indicating device at the remote station, a switch adjacent the door controlling said indicating device and means on said door operating said switch when the door is in closed position.

10. The combination set forth in claim 8 in which said distributor member comprises a substantially cylindrical sleeve having a valve member slideable therein, said valve member having an external annular groove defining two end portions and a passageway therethrough, said valve member being constructed and arranged, when in one of its operating positions to provide communication through said passageway between one of said pair of ports in said distributor member and said additional port and to provide communication through said annular groove between said inlet port and the other of said pair of ports, one of said end portions closing said return port and in the other operating position to provide communication between said first port of said pair of ports and said inlet port and to provide communication between said return port and said additional port through said annular groove, and means to move said valve member from one of said operating positions to the other.

11. The combination set forth in claim 8 in which the means connecting the outlet of said remote station pump to one of the pairs of ports of said cylinder comprises a line having a one way check valve which permits flow only from said pump to said cylinder and the return port in said distributor member is connected by a line to said first named line between the check valve and the cylinder port.

12. A control system comprising a local control station, a remote control station, a pair of pumps each having an inlet and an outlet, a source of fluid for said pumps, one of said pumps being at the remote station, a hydraulic cylinder having a piston slideable therein, said cylinder having a port on one side of said piston and a pair of ports on the other side of said piston, means connecting the outlet of said remote station pump to one of said pair of ports of said cylinder, a distributor member having a pair of ports connected respectively to the other ports of said cylinder, said distributor member also having an inlet port connected to the outlet of the other pump and a return port connected to the cylinder port to which the remote pump is connected, means in said distributor member movable from an intermediate to either of two operating positions, normally closing said inlet port when in intermediate position and connecting said inlet port to one or the other of the pair of ports of said distributor member respectively when in said operating positions, said distributor member having an additional port connected to said fluid source, said means in said distributor member closing said return port when in intermediate and one of said operating positions and connecting said return port and said additional port when in the other of said operating positions and a pressure accumulator connected to the inlet port of said distributor member.

13. The combination set forth in claim 12 in which an additional pump is provided at said local station having its inlet connected to the reservoir associated with the other pump, and its outlet connected to the inlet port in said distributor member, a check valve positioned between said additional pump outlet and said inlet port, a check valve positioned between said pressure accumulator and said inlet port and a check valve positioned between the outlet of said other pump and said pressure accumulator.

14. The combination set forth in claim 12 in which the outlet of said remote station pump is also connected to the inlet port of said distributor member and a control valve is positioned between said outlet and said inlet port.

15. The combination set forth in claim 12 in which the source of fluid for said pumps comprises a pair of reservoirs, one positioned adjacent each of said pumps and the additional port in said distributor member is connected to both of said reservoirs.

16. The combination set forth in claim 12 in which said distributor member comprises a substantially cylindrical sleeve having a valve member slidable therein, said valve member having a pair of spaced annular grooves defining a pair of end portions and a central portion, said distributor member having two discharge ports connected to said additional port, said valve member being constructed and arranged, when in intermediate position, for said central portion to close said inlet port, for one of said end portions to close said return port and for said annular grooves to provide communication between said pair of ports of said distributor member and said additional port; when in one of said operating positions for one of said end portions to close said return port and one of said discharge ports, for the other of said end portions to close said additional port, and for said annular grooves to provide communication between said inlet port and one of said pair of ports and the other of said discharge ports and the other of said pair of ports respectively and when in the other operating position, to provide communication between said return port and one of said discharge ports, between said additional port and one of said pair of ports, between said inlet port and the other of said pair of ports and for one of said end portions to close said other discharge port.

17. The combination set forth in claim 12 in which the means in said distributor member comprises a slidable valve member, a pivotally mounted lever is operatively connected to said valve member to actuate the latter, a casing is provided having a piston slidable therein and connected to said lever, a second pivotally mounted lever is connected to said casing, an electro-magnet is provided having a pivotally mounted latch arm normally restraining said second lever from movement when the electro-magnet is energized, a coil spring operatively connected to said first lever normally urges the latter in direction to move the valve member to closed position and a coil spring in said casing of greater strength than said first coil spring retains the first lever in intermediate position when said second lever is restrained by said latch arm.

18. The combination set forth in claim 17 in which a coil spring is associated with said second lever to pivot the latter when said first lever is raised.

19. The combination set forth in claim 17 in which a switch at said remote station controls said electro-magnet.

20. The combination set forth in claim 17 in which a switch at said remote station controls said electro-magnet and a second switch is in series with said first switch and said electro-magnet.

21. The combination set forth in claim 17 in which a switch is associated with said first lever and actuated thereby when the lever is pivoted, said switch controlling an indicating device at the local station.

22. The combination set forth in claim 17 in which said piston controls a piston rod, a slidably mounted door is provided operatively connected to the piston rod of said hydraulic cylinder and movable thereby from open to closed position, an indicating device at the remote station, a switch adjacent the door controlling the indicating device at the remote station, means on said door operating said switch when in closed position, a second switch associated with said first lever and actuated thereby when said lever is pivoted, an indicating device at the local station, said two switches controlling said indicating device at the local station when the door is closed.
